UNITED STATES PATENT OFFICE.

LEANDER C. HALL, JR., OF PHILADELPHIA, PENNSYLVANIA.

DESIGN FOR A MITT.

SPECIFICATION forming part of Design No. 19,180, dated June 25, 1889.

Application filed January 5, 1889. Serial No. 295,567. Term of patent 7 years.

To all whom it may concern:

Be it known that I, LEANDER C. HALL, Jr., a citizen of the United States, residing in the city and county of Philadelphia, State of Pennsylvania, have invented and produced a new and original Design for Mitts, of which the following is a specification, reference being had to the accompanying drawing.

The leading features of my design for the ornamentation of a mitt are parallel stripes on the back of the hand portion thereof extending from the outer edge of the wrist portion to the end of the finger portion, cross-stripes at right angles to the first stripes on the wrist portion, and tips of the fingers and the thumb portion of a different shade from the main part of said finger and thumb portions.

In the accompanying drawing, to which reference is made, A represents a mitt, on the back of which are shown broad parallel stripes B B, extending from the outer edge of the wrist portion to the end of the finger portion.

C C represent cross-stripes at a right angle to the stripes B B on the wrist portion. 25

D represents a tip or portion of the end of the finger and the thumb portions, having a different shade from that of the main part of said portions.

Having thus described my invention, what I claim as new, and desire to secure by Letters Patent, is—

The design for the ornamentation of a mitt herein shown and described, consisting in the back of the hand portion having parallel stripes extending to the ends thereof and the wrist portion having cross-stripes, and the tip and wrist portions being of a different shade or appearance from the main portion of the thumb and hand portions. 35

LEANDER C. HALL, JR.
